(57) **CLAIM**

The ornamental design for a showerhead with integral valve, as shown and described.

DESCRIPTION

FIG. 1 is a perspective view of a showerhead with integral valve showing my new design;

FIG. 2 is a front elevational view thereof;

FIG. 3 is a top plan view thereof;

FIG. 4 is a left side view thereof, the opposite side being a mirror image of the side shown; and,

FIG. 5 is a rear view thereof.

The broken line showing of portions of the face and a handle is included for the purpose of illustrating and forms no part of the claimed design.
